UNITED STATES PATENT OFFICE.

OLOF E. WENNBERG, OF CHICAGO, ILLINOIS.

MOLD FOR CONCRETE WALLS.

SPECIFICATION forming part of Letters Patent No. 783,767, dated February 28, 1905.

Application filed April 15, 1904. Serial No. 203,342.

To all whom it may concern:

Be it known that I, OLOF E. WENNBERG, a citizen of the United States, residing at Chicago, in the county of Cook and State of Illinois, have invented a new and useful Improvement in Molds for Concrete Walls, of which the following is a specification.

This invention relates to removable molds for constructing concrete or retaining walls of any plastic material.

The invention comprises side walls for the mold, the said side walls being held in place by angled interlocking hooks detachable from each other and inclosing between them the two side walls.

The invention consists in the novel features of construction and combination of parts hereinafter described, particularly pointed out in the claims, and shown in the accompanying drawings, in which—

Figure 1 is a perspective view showing the practical application of my device in wall-building. Fig. 2 is a transverse section through the mold and wall, the section being taken through the longitudinal center of the hook members. Fig. 3 is a perspective view of the frame formed by the hook members when interlocked, the side walls being omitted. Fig. 4 is a detail perspective view of a method of locking the hook members together. Fig. 5 is an end elevation showing a plurality of molds arranged in vertical alinement. Fig. 6 is a side elevation of Fig. 5. Figs. 7 and 8 are detail views of construction.

In constructing my mold I employ the side members A, which may be plain rectangular boards, and two right-angled hook members B and C, though it will be understood that the angle may be varied in particular cases and that the hook members B and C may be made in a great variety of sizes and when interlocked will form frames of various dimensions, each frame having also a limited amount of adjustability.

For clearness I have designated the hook member having its horizontal portion resting on the top of the side members A or on the upper edges of same B and the one upon which the side members A rest C; but it will be understood that the members B and C are iden-

tical in construction, and a detail description of one will apply to both.

Adjacent the free end of the horizontal member of each of the hook members B and C are formed a plurality of perforations D, 55 and the end of this member is bifurcated, as at D', and small perforations are formed on each side of the bifurcation to receive the points of a staple E, as shown most clearly in Fig. 4. The vertical portion of each hook member is reduced to form a pin F, adapted to fit in the perforations D and also to rest in the bifurcations D' of the coacting hook member.

In the construction of a wall such as is shown in Figs. 1 and 2 the hook members C 65 are placed in position. The sides A are then arranged in place, being spaced apart the desired width of the wall, and the hook member B is then arranged with the perforated portion resting upon the upper edges of the sides 70 A, one of the perforations engaging the pin F of the hook member C, and the pin F of the vertical portion of the hook member B likewise engages a corresponding perforation in the horizontal portion of the hook member 75 C. The concrete or other plastic material of which the wall is to be composed is filled in the mold to a level with the upper edges of the side members A. When the material has set, the hook member B is readily removed, 80 and the boards or planks forming the sides A are taken down and the hook members C readily withdrawn from the wall. The hook members C are then placed in position upon the portion of the wall just formed and a second layer superimposed thereon. The holes left in the wall are plastered and the work continued until the wall has reached the desired height. Should the sides be spaced too 85 far apart to permit the use of the perforations D, the pins F engage the bifurcations D' and are held against sliding out of the same by means of the staples E.

When desired, as in the case of retaining-walls for railroad embankments, the size of 95 the hook members is changed, and the members G, corresponding to the members B, are formed with a greater angle than that of a right angle, and the hook members H are formed with a right angle, and the frames 100

composed of the members G and H are built up one above the other, as shown in Figs. 5 and 6, each of the hook members H supporting a set of the side pieces A. Where one side of the wall is inclined, as shown in Fig. 5, the length of the horizontal portions of the hook members G and H are graduated, as shown in Fig. 5.

It will be obvious that the hook members B, C, G, and H may be made in many sizes and angled in any manner desired without in any way departing from the spirit of my invention, and I do not desire to be limited to any special size or shape of hook member.

Having thus fully described my invention, what I claim as new, and desire to secure by Letters Patent, is—

1. A mold of the kind described comprising side pieces, angled hook members each having

a perforated portion and the remaining portion of each hook member having a reduced end, one of said hook members being adapted to support the side pieces and the other being adapted to rest transversely across the upper edges of the side members.

2. The combination with the side pieces, of two angled hook members having each a reduced end portion and a bifurcated end portion, and having perforations formed adjacent the bifurcated end, the reduced end of one hook member being adapted to engage the bifurcation of the other hook member, and staples adapted to lock the reduced ends against horizontal movement in the said bifurcations.

OLOF E. WENNBERG.
